RIVET BUCKER TOOL

David N. Goldberg, Wheeling, W. Va.

Application March 21, 1945, Serial No. 583,888

5 Claims. (Cl. 78—53.5)

1

This invention relates to a rivet buckler primarily adapted for use in installing the rivets for brake linings, although the same may have other uses.

The principal object of the invention is to provide a tool of the character aforesaid by means of which a rivet may be held in position under pressure while the end thereof is upset to lock the same in position.

A further object of the invention is to provide a tool of the character aforesaid which is capable of supporting itself on the work being riveted, and which is adjustable in a universal manner to adapt the same for use with work of varying sizes and shapes.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail side elevation, partly broken away and in section, of a tool constructed according to an embodiment of this invention.

Figure 2 is a bottom plan view of the tool.

Figure 3 is a sectional view, partly in elevation, taken on the line 3—3 of Figure 1.

Figure 4 is a fragmentary bottom plan of the adjustable lever supporting block.

Figure 5 is a side elevation of a modified form of tool.

Figure 6 is a top plan of the tool, as shown in Figure 5.

Figure 7 is a transverse section taken on the line indicated 7—7 in Figure 5.

Figure 8 is a fragmentary sectional plan taken on the line indicated 8—8 of Figure 5.

Referring to the drawings, and first to Figures 1 to 4, inclusive, the numeral 10 designates generally a clamping head, which is formed with an upper cross bar 11, having depending from the opposite ends thereof a pair of arms 12, provided with elongated slots 13. The bar 11 has extending forwardly therefrom a pair of divergent jaw supporting arms 14, having extending downwardly from the forward end thereof work clamping jaws 15.

A rivet engaging jaw 16, having a cap 17 formed integral therewith, or secured thereto, is threadably mounted on the forward end of a threaded lever, or bar 18. The lever, or bar 18

is threaded through a block, or nut 19, disposed between the depending arms 12 and the block, or nut 19, engages between a pair of adjustable blocks 20, having openings 21 transversely therethrough, through a selected one of which a pin 22, extending through the arm 12, is adapted to engage. In this manner each block 20 may be adjustably supported lengthwise of a slot 13.

The nut, or block 19, is rockably supported from the blocks 20 by means of a pair of aligned screws 23, which are extended loosely through openings 24 in the blocks 20, and are threaded as at 25 into the block, or nut 19.

Referring now to Figures 5 to 8, inclusive, the numeral 10^a designates generally a head, which is formed of a cross bar 11^a, having depending from the opposite ends thereof a pair of depending arms 12^a formed with elongated slots 13^a. The cross bar 11^a also has extending forwardly therefrom a pair of divergent jaw supporting arms 14^a, and a work clamping jaw 15^a depends from the forward ends of each divergent arm 14^a. A rivet engaging head, or jaw 16^a is disposed between the jaws 15^a and has formed integral therewith, or secured thereto, a cap 17^a, which is threaded on the forward end of an elongated tubular lever 18^a. The lever 18^a is slideable through a sleeve 26 and is adapted to be adjusted lengthwise of the sleeve 26 by means of a locking pin 27, engaging through a selected opening 28 formed in the sleeve 26, and also through a selected opening 29, which is formed in the tubular lever, or bar 18^a.

Preferably the bar 18^a is formed with diametrically opposed openings 29 within which the pin 27 is adapted to engage. The outer end of the pin 27 may be formed with a knurled head 30 to facilitate removing, or replacement, of the pin in selected openings of the sleeve 26 and the bar, or lever 18^a.

The sleeve 26 is rockably supported between a pair of adjustably positioned blocks 31, which loosely engage in the slots 13^a, and the blocks 31 are formed with holes 32, within a selected one of which a locking pin 33, engaging transversely through an arm 12^a, is adapted to extend. The sleeve 26 is rockably supported between the blocks 31 by means of a pair of pins 34, which are extended through holes 35, formed in the blocks 31 and the inner ends of the pins 34 loosely engage in holes 36, which are formed in the sleeve 26.

In the use of the tool, the arms 14 are positioned over the work with the members 15 abutting the forward face thereof. The blocks 20 are adjusted vertically of the legs 12 by means of the

pins 22 so as to position the work contacting member 16 at approximately the same height as the rivet, or the like, to be operated upon. The lever 18 is threadably adjusted lengthwise of nut 19, and is initially disposed with the free end above the horizontal with the member 16 in contact with the rivet head. Upon depressing the lever, the member 16 forces the rivet, or the like, through the work and maintains a pressure thereon while being clenched, or otherwise operated upon, at the forward face of the work.

What I claim is:

1. A rivet bucking tool comprising a head, including a cross bar, having a leg depending from each end thereof, each of said legs having an elongated slot, said head further including a pair of forwardly extending diverging arms terminating at their forward ends in down turned abutment members adapted to engage one face of a relatively thin piece of work, a pair of blocks extending into the slots of said legs, each of said legs having a pair of aligned bores opening into its slot, and each of said blocks having a plurality of vertically spaced bores adapted to be registered selectively with the aligned bores of the said leg associated therewith, pins for extension through the registered bores of the legs and blocks, a sleeve extending between said legs transversely thereof and between said blocks, said sleeve having a pair of aligned bores extending therethrough transversely thereof, said blocks having transversely aligned bores adapted to be registered with the aligned bores in said sleeve, a pin for extension through the registered bores in the sleeve and blocks for pivotally connecting the sleeve with said head, a lever extending through said sleeve, a contact member at the forward end of said lever, said sleeve and lever having spaced bores adapted for selective registry with each other, and a pin for extension through registered bores in the sleeve and lever for adjustably connecting them together.

2. A rivet bucking tool comprising a head, including a cross bar, having a leg depending from each end thereof, a pair of arms extending forwardly from said cross bar and terminating in down turned abutments adapted to engage one face of a relatively thin piece of work, a pair of vertically adjustable blocks connected to said legs, a sleeve extending between said legs transversely thereof and between said blocks, said sleeve having a pair of transversely aligned bores extending therethrough, said blocks having aligned bores adapted to be registered with the aligned bores in said sleeve, a pin for extension through the registered bores in the sleeve and blocks for pivotally connecting the sleeve with said head, a lever extending through said sleeve a contact member at the forward end of said lever, said sleeve and lever having spaced bores adapted for selective

registry with each other, and a pin for extension through registered bores in the sleeve and lever for adjustably connecting them together.

3. A rivet bucking tool, comprising a head, including a cross bar having a leg depending from each end thereof, a pair of arms extending forwardly from said cross bar and terminating in down turned abutment members adapted to engage one face of a relatively thin piece of work, a pair of vertically adjustable blocks connected to said legs, a sleeve extending between said legs transversely thereof and having a pivotal connection with said blocks, a lever extending through said sleeve and being adjustable lengthwise thereof, and a contact member at the forward end of said lever.

4. A rivet bucking tool, comprising a head, including a cross bar, having a leg depending from each end thereof, each of said legs having an elongated slot, a pair of arms extending forwardly from said cross bar and terminating in down turned abutment members adapted to engage one face of a relatively thin piece of work, a sleeve extending between said legs transversely thereof, a pair of blocks slidably engaging in said slots, means for pivotally connecting said sleeve with said blocks, a lever extending through said sleeve and being adjustable lengthwise thereof, and a work contacting member at the forward end of said lever.

5. A rivet bucking tool, comprising a head, including a cross bar having a leg depending from each end thereof, a pair of arms extending forwardly from said cross bar and terminating in down turned abutment members adapted to engage one face of a relatively thin piece of work, a pair of vertically adjustable blocks connected to said legs, a threaded block extending between said legs transversely thereof and having a pivotal connection with said first blocks, a lever adjustably threaded through said threaded block and being adjustable lengthwise thereof, and a contact member at the forward end of said lever.
